PIPE CLEANER

Jasper Whiting, Boston, Mass.

Application March 24, 1936, Serial No. 70,560

3 Claims. (Cl. 131—13)

This invention relates to implements designed for use in cleaning the inner walls of the bowls of smoking pipes.

After a pipe has been smoked for some time, 5 the inside of the bowl becomes carbonized and a "cake" builds up on it. It is desirable from time to time to remove more or less of this accumulation but in a controlled manner suited to the requirements of the particular conditions and 10 the preferences of the smoker. So far as I have been able to learn, no satisfactory tool for performing this function has heretofore been available. The present invention aims to supply this need. In addition, it is also an object of the invention 15 to devise an implement of this character which will be sturdy and substantial in construction, economical to manufacture, and capable of being folded into a small space suitable for carrying in the pocket.

The nature of the invention will be readily understood from the following description when read in connection with the accompanying drawing, and the novel features will be particularly pointed out in the appended claims.

In the drawing,

Figure 1 is a side view of a pipe cleaner constructed in accordance with this invention;

Fig. 2 is an end view of the device shown in Fig. 1;

Fig. 3 is a perspective view of the cleaner;

Fig. 4 is an edge view of the cleaner;

Fig. 5 is a sectional view on approximately the line 5—5, Fig. 4; and

Fig. 6 is a perspective view showing the device 35 in its closed or folded condition.

The construction shown in the drawing comprises two jaws indicated, respectively, at 2 and 3. These jaws are pivotally connected together by a pin or rivet 4. Also, each jaw has a handle pivoted to it, that for the jaw 2 being indicated at 5, while the other handle is shown at 6. The pivot pins connecting these handles to their respective jaws are indicated at 7 and 8, respectively. A spring 10 coiled around the pivot 4 has its opposite legs lying under the respective pivot pins 7 and 8, and it is so biased or tensioned that it tends normally to hold the jaws 2 and 3 in contact with each other, as shown in Figs. 1 and 2. By compressing the handles the jaws may be 50 spread apart.

Preferably the jaws are made of channel section, and of any suitable metal, such as stainless steel, and they are located back to back so that the free edges of one jaw point away from the 55 opposite jaw. These edges may be sharpened

or serrated, or a combination of these two edge forms may be used. In any event, when they are placed inside the bowl of the pipe, as shown in Fig. 1, the handles may be compressed to expand the jaws sufficiently to bring them into scraping engagement with the inner walls of the bowl. Then by rotating the bowl around the jaws, the entire wall surface may be scraped and cleaned. This entire operation is under the control of the user so that he can cut away as much of the 10 cake on the inside of the bowl as he desires.

When the device is not in use, it may be folded into the compact form shown in Fig. 6. This object is conveniently realized by making the handles 5 and 6 of channel section and sufficiently wider and longer than the jaw members so that each handle may be folded into position to enclose its respective jaw. Also, by suitably rounding the ends any sharp projections that would wear holes in the pocket can be eliminated. 20 Upon opening the cleaner, the square surfaces a—a at the end of each jaw engage similar surfaces on the handle, one of which is shown at b in Fig. 6, and stop the relative swinging movement of these parts when the handles are substantially in alinement with the jaws.

The channel form of the jaws and handles is of advantage not only in facilitating the folding of the device, as just described, but also in producing a much stronger construction from a 30 given weight of metal. In addition, it facilitates the manufacture of a sturdy but inexpensive hinge or pivot construction between the two jaws. As best shown in Figs. 4 and 5, a section of the bottom of the upper jaw 2 is punched down to 35 form two downwardly extending ears c—c which are squeezed together, or inset sufficiently, to extend between two upwardly projecting ears d—d formed by punching upwardly a section of the main web of the upper jaw 3. After, or in connection with, the punching operation, the ears may be trimmed or shaped to the desired contours, and the holes for the pivot 4 are made.

The invention thus provides a pipe cleaner which has proved in actual use to be highly effective, convenient to use, and extremely compact. The fact that the jaws are of channel or grooved form and are located back to back, provides four scraping or cutting edges so spaced that they do not dig in. Their scraping action also 45 is facilitated by notching the edges in such a manner as to provide flat topped teeth, as best shown in Fig. 3, the teeth on the edges of each jaw preferably being staggered with reference to each other. By providing the device with folding 50

handles which enclose the jaws, the cleaner can be carried in the pocket without danger of soiling the clothing.

While I have herein shown and described a preferred embodiment of my invention, it will be evident that the invention may be embodied in other forms without departing from the spirit or scope thereof.

Having thus described my invention, what I desire to claim as new is:

- 10 1. In a pipe cleaner, the combination of two jaws, each of said jaws consisting of one-piece channel members, handles connected to said jaws for operating them, said handles being of channel section and the handles being pivoted to their respective jaws so that they may be swung into folded relationship to the jaws, said handles being of such dimensions as to receive and to substantially enclose said jaws when the parts are 15 in their folded relationship, both said jaws and said handles being disposed substantially back to back when the device is in its open or unfolded condition, each of said jaws having intermediate their lengths parts projecting toward the other channel member and apertures between said parts, and a pin passing through said parts and lying substantially within the apertures.
- 20 2. In a pipe cleaner, the combination of two jaws, each of said jaws consisting of one-piece channel members, handles connected with said jaws for spreading the jaws when the handles are compressed, a spring serving normally to urge said handles away from each other, said jaws being of sheet metal and being arranged substantially back to back, whereby the edges of each

jaw extend away from the other jaw, one of said jaws having a pair of integral ears extending from the back thereof and the other having parts projecting therefrom, said ears overlapping a portion of the other jaw at a point intermediate the length of the latter jaw at which said projecting parts are located, and a pivot pin extending through said ears and said projecting parts of the latter jaw and hinging the two jaws together, said handles being of channel section and being pivoted to the respective jaws for swinging movement thereon into extended operative relationship to the jaws and into folded relationship thereto where they substantially enclose the jaws.

3. In a pipe cleaner, the combination of two jaws pivoted together for relative movement toward and from each other, each of said jaws consisting of one-piece channel members, handles connected to said jaws for operating them, the bottoms of said channel members being apertured, a pivotal connection having a pivot lying within the apertures, and resilient means operated by the handles and connected to the pivot, said resilient means having a part thereof positioned in the apertures, both handles being of channel section and pivoted to their respective jaws so that they may be swung into folded relationship to the jaws, said handles being of such dimensions as to receive and to substantially enclose said jaws when the parts are in their folded relationship, and both said jaws and said handles being disposed substantially back to back when the device is in its open or unfolded condition.

JASPER WHITING. 35
